(57) **CLAIM**

The ornamental design for a modular bottle as shown and described.

DESCRIPTION

FIG. 1 is an exploded right front perspective view of a modular bottles showing all components of a first embodiment of my design;

FIG. 2 is a top plan view of the modular bottle of FIG. 1;
FIG. 3 is a bottle plan view of the modular bottle of FIG. 1;
FIG. 4 is an exploded front view of the modular bottle of FIG. 1;

FIG. 5 is an exploded rear view of the modular bottle of FIG. 1;

FIG. 6 is an exploded left side view of the modular bottle of FIG. 1;

FIG. 7 is an exploded right side view of the modular bottle of FIG. 1;

FIG. 8 is a right front perspective view of the assembled modular bottle of FIG. 1;

FIG. 9 is a top plan view of the modular bottle of FIG. 8;
FIG. 10 is a bottom plan view of the modular bottle of FIG. 8;

FIG. 11 is a front view of the modular bottle of FIG. 8;

FIG. 12 is a rear view of the modular bottle of FIG. 8;

FIG. 13 is a left side view of the modular bottle of FIG. 8;
FIG. 14 is a right side view of the modular bottle of FIG. 8;
FIG. 15 is an exploded right front perspective view of a modular bottle showing all components of a second embodiment of my design;

FIG. 16 is a top plan view of the modular bottle of FIG. 15;
FIG. 17 is a bottle plan view of the modular bottle of FIG. 15;

FIG. 18 is an exploded front view of the modular bottle of FIG. 15;

FIG. 19 is an exploded rear view of the modular bottle of FIG. 15;

FIG. 20 is an exploded left side view of the modular bottle of FIG. 15;

(Continued)

FIG. 21 is an exploded right side view of the modular bottle of FIG. 15;
 FIG. 22 is a right front perspective view of the assembled modular bottle of FIG. 15;
 FIG. 23 is a top plan view of the modular bottle of FIG. 22;
 FIG. 24 is a bottom plan view of the modular bottle of FIG. 22;
 FIG. 25 is a front view of the modular bottle of FIG. 22;
 FIG. 26 is a rear view of the modular bottle of FIG. 22;
 FIG. 27 is a left side view of the modular bottle of FIG. 22;
 and,
 FIG. 28 is a right side view of the modular bottle of FIG. 22. The broken lines showing portions of the modular bottle are included for the purpose of illustrating portions of the article that form no part of the claimed design.

1 Claim, 12 Drawing Sheets
